UNITED STATES PATENT OFFICE

173,091

NAPKIN DISPENSER OR THE LIKE

Harry O. Sandberg, Boston, Mass.

Application December 29, 1953, Serial No. 28,284

Term of patent 3½ years

(Cl. D44—24)

To all whom it may concern:

Be it known that I, Harry O. Sandberg, a citizen of the United States, residing at Boston, Massachusetts, have invented a new, original, and ornamental Design for a Napkin Dispenser or the like, of which the following is a specification, reference being had to the accompanying drawing, forming a part thereof.

Fig. 1 is a front perspective view of a napkin dispenser or the like, showing my new design; and Fig. 2 is a rear perspective view thereof.

I claim:

The ornamental design for a napkin dispenser or the like, substantially as shown.
